UNITED STATES PATENT OFFICE.

WILLIAM SPARKS, THEODORE JOHNSON SCOFIELD, LLOYD ELMER JOHNSON, AND FRED WILLIAM BILLIG, OF JACKSON, MICHIGAN, ASSIGNORS TO THE SPARKS-WITHINGTON COMPANY, OF JACKSON, MICHIGAN, A CORPORATION OF OHIO.

SIGNALING DEVICE.

Application filed May 18, 1927. Serial No. 192,330.

This invention relates to certain new and useful improvements in signaling devices.

The main object of the invention is the production of a novel signaling device particularly designed for use on automobiles, motor boats and the like, and capable of producing a comparatively loud signal that will carry long distances and is of a musical tone or combination of musical tones, preferably of a harmonious character.

More detailed objects relate to the simplicity and strength of the structure and the detailed form, arrangement and association of the parts thereof, all as will more fully appear from the following description, taken in connection with the accompanying drawings, in which:

Figure 1 is a top plan view of a device of this invention.

Figure 2 is a section on line 2—2, Figure 1.

Figure 3 is a section on line 3—3, Figure 1.

Figure 4 is a fragmentary section through the diaphragm casings or chambers in the upper portion of the structure of the device.

Figure 5 is a section through the end portions of the projectors.

Figure 6 is a section on line 6—6, Figure 2.

The structure as herein illustrated consists of a rotary electric motor —1— having its armature shaft substantially vertically disposed and the upper end wall —2— of the case of the motor is of substantially circular form and provided with a depending tubular boss —3— in which the upper end of the armature shaft —4— is journaled.

The lower end of the armature shaft —4— extends through an opening in the U-shaped case —7— and may be provided with an adjustable bearing —5— carried by the end or cross-wall —6— of the U-shaped motor case —7—. The ends of the U-shaped motor case —7— are secured to the flanges —8— and —9— respectively formed upon the upper end wall —2—. The usual armature —10—, pole pieces —11— and field coils —12— are provided.

The actual structure of the motor may vary widely, the essential being a means for producing rotary movement, and any form of electric motor may be utilized which is capable of driving a rotary compressor which constitutes a portion of the device, and for this purpose the end wall or head —2— is formed with a circular chamber or cylinder

—14— on the side opposite the electric motor —1—, and this cylindrical recess or chamber is eccentric with respect to the armature shaft —4—, and to the rotor shaft —15— which is aligned with the armature shaft —4—, and may be connected to the rotor —13— in any suitable manner, as for instance formed integrally with the rotor.

The rotor shaft extends into and is journaled in the boss —3— and may terminate a short distance above the upper end of the armature shaft —4—, and is connected to the armature shaft for simultaneous rotary movement, while permitting relative longitudinal movement in any suitable manner, as by a key —50— extending into slots formed in the adjacent ends of the rotary shaft, and the armature shaft for locking the two against relative rotary movement, the key being positioned at an intermediate point along the bearing —3—.

In effect, the rotor shaft —3— and the armature shaft —4— are a sectional armature shaft and for the purpose of the claims of this application may be so considered.

The armature shaft being concentric with the end head —2— and the rotor —13— being concentric with the armature shaft, the rotor is eccentrically positioned in the cylinder or chamber —14— by reason of the fact that the said cylinder is formed eccentrically in the end head.

The end head —2— is further formed with an air storage chamber —17—, in this instance arranged concentrically with the wall of the cylindrical chamber —14— and extending around the cylindrical chamber throughout slightly more than one-half of its circumference. This storage chamber is in communication with the pressure side of the rotary pump through a port —18— in the wall of the chamber —14—, and through this port air under pressure is ejected by the rotor —13— from the chamber —14— and for effecting this result the rotor —13— includes one or more, in this instance three movable blades —19— slidably mounted in grooves or recesses in the rotor, and preferably spaced equal distances apart and adapted to be thrown out by centrifugal force as the rotor —13— is driven by the armature shaft —4—.

The compressor chamber —14— is formed with an air inlet —20— at the suction side of

the compressor, and which air inlet penetrates the bottom wall of the compressor chamber and leads into the casing —51— which encloses the electric motor —1—. This 5 casing is usually imperforate and for the purpose of admitting air to its interior, it is formed with a struck-up portion —52— interrupting the continuity of the casing wall and forming a passageway —53— leading to 10 a passageway —54— through the flange —55— on the end head —2—, whereby air may be freely supplied to the inlet —20— of the compressor and without the production of vacuum within the casing —51—.

15 Mounted upon the upper end of the head —2— and covering the compressor chamber —14— and the storage chamber —17— is a horn body —56— secured to the head —2— in any suitable manner, as by screws —57—, 20 suitable packing being interposed between the body and the head to prevent the escape of air when compressed. The body —56— is formed at its opposite sides with two vertical conduits or passageways —58— preferably of similar form and shape, and leading to two longitudinal conduits formed in the bosses —59— likewise of similar form and shape.

The structure here illustrated is designed 30 to include two sound-producing structures, and except for the length of the projectors —60— these sound-producing devices are of similar form, shape and structure, and a description of one constitutes a description of 35 both. The projectors —60— differ in this illustration in that one of them is somewhat longer than the other for the purpose of producing different notes which by suitable adjustment of the devices can be made harmonious in character.

40 In each case the projector —60— has its rear end threaded into the front end of one of the bosses —59— on the horn body and a tube —61— is threaded into the boss so as to substantially contact with the rear end of the projector —60—, and this tube projects rearwardly from the boss —59—.

45 Each boss —59— has a circumferentially enlarged intermediate portion forming an annular chamber —62— surrounding the tube —61— and in communication with the respective conduits —58—. The rear end of each boss is internally enlarged with respect to the front end and is threaded for the reception of an externally threaded tubular boss —63— formed concentrically at the base of a cup-shaped member —64— which may be locked in any desired position with respect to boss —59— by means of lock nut —65—.

50 The internal diameter of the boss —63— is somewhat greater than the external diameter of the tube —61— so as to form an annular passageway around the tube leading from chamber —62— to the interior of the cup 55 shape member —64—. The external wall of

the cup-shape member —64— is externally threaded for cooperative engagement with the interiorly threaded flange upon a cup-shape cap —66— and this cap —66— is formed with a radial shoulder —67— between 70 which and the end of the cup-shape member —64— a thin metallic diaphragm —68— has its edge confined.

The size and arrangement of the parts is such that when the diaphragm is positioned, 75 as described, it extends across and normally closes the rear open end of the tube —61— and preferably the rear open end of tube —61— is flared, as indicated at —69—.

It is found that the air in the chamber between the diaphragm —68— and the cap —66— varies in pressure somewhat in accordance with the temperature to which the device is subjected, thereby varying the pressure upon the diaphragm —68— which in turn effects the operation of the signaling device, and in order to maintain the device uniform in operation, the cap —66— is provided with one or more openings —70— leading to the chamber between the diaphragm and the 85 cap to permit the entrance of air to or the exit of air from said chamber to maintain a normal pressure, irrespective of temperature changes.

These openings may, if desired, be covered 90 on the inside by plate —71— and on the outside by disk —72— for appearance sake so long as sufficient space is provided, as for instance by small grooves or passageways 95 —73— for the escape or entrance of air.

In operation, when the armature shaft is rotated, air entering through inlet —20— is compressed and ejected through outlet —18— into storage chamber —17—, and thence passes thru conduits —58— to the respective 105 chamber —62— and thence through annular passageways —75— to the interior of the cup-shape member —64— into contact with the front side of diaphragm —68— whereby diaphragm —68— is caused to move slightly 110 rearwardly to permit the escape of the air through the tube —61—.

The resiliency of the diaphragm and the variation in pressure, due to the escape of air, 115 returns the diaphragm to the position where it closes or substantially closes the inlet to tube —61—, and the operation is then repeated, thereby causing a rapid vibration of the diaphragm over the mouth of the tube —61—, producing and causing the projectors to emit 120 a musical tone. The spacing and supporting member —76— may be interposed between the end of the shorter projector —60— and an intermediate portion of the latter, and this spacing and supporting member may be 125 formed with a groove for receiving the edge of the shorter projector and with an inclined surface conforming to the external wall of the longitudinal projector.

130 By adjusting the cup-shape member —64—

in the boss —59— a proper positioning of the diaphragm —68— can be effected to produce the desired note, and the member —64— may then be locked in place by lock nut —65—.

5 The horn body —56— is provided with a lubricant chamber —90— reduced at its lower end to form a constricted passageway leading to the compressor-chamber —14— and this chamber is preferably filled or partially filled 10 with a lubricant absorbing and retaining means, as for instance, felt or wicking —91— and the upper end of the chamber is normally closed by a removable screw —92—. In order to maintain proper lubrication of the 15 compressor and motor it is only necessary to remove the screw —92— and place lubricant in the chamber —90— from which lubricant is fed, as required, to the compressor. The chamber —90— as here shown, is intermediate the bosses —59—.

And altho we have shown and described a specific structure as constituting the perhaps preferred embodiment of the invention, we do not desire to restrict ourselves to the details of

25 form, construction or arrangement of the parts thereof, except as the same may be specifically included in the claims hereto appended.

We claim:

30 1. A signaling device comprising a motor, a rotary compressor driven thereby, a horn body having a passageway in communication with the pressure side of the compressor and formed at its upper end with a tubular boss, a projector having its rear end mounted in said boss, a tube mounted in the boss, a diaphragm chamber mounted in the boss and spaced from the exterior wall of the tube to form an annular passageway, a diaphragm in 35 said chamber extending across the end of said tube, and means for maintaining atmospheric pressure on the side of the diaphragm opposite the tube.

2. A signaling device comprising a motor, a 45 rotary compressor driven thereby, a horn body having a passageway in communication with the pressure side of the compressor and formed at its upper end with a tubular boss, a projector having its rear end mounted in said boss, a tube mounted in the boss, a diaphragm chamber mounted in the boss and spaced from the exterior wall of the tube to form an annular passageway, an imperforate diaphragm in 50 said chamber extending across the end of said tube, and means for maintaining atmospheric pressure on the side of the diaphragm opposite the tube.

3. A signaling device comprising a motor, a 60 rotary compressor driven thereby, a horn body mounted on the compressor and having a passageway in communication with the pressure side of said compressor, said horn body formed at its upper portion with a pair of spaced tubular bosses, projectors of different 65 length mounted in the bosses and extending

forwardly from the horn body, tubes mounted in respective bosses and extending rearwardly from the projectors to a point beyond the bosses, diaphragm chambers secured to respective bosses and in communication with the passageway through the horn body and positioned at the rear of the bosses, and diaphragms in respective diaphragm chambers extending across the rear end of said tubes.

4. A signaling device comprising a motor, 70 a rotary compressor driven thereby, a horn body having a passageway in communication with the pressure side of the compressor and terminating at its upper end in a transverse tubular boss, a projector mounted in said boss and in communication with said passageway, a cup-shape body threaded into the boss and in communication with the projector, a tube mounted in the boss and extending rearwardly into the cup-shape body, a cap 75 threaded on to the cup shape body and a diaphragm positioned between the cup-shape body and the cap and extending across the rear end of said tube.

5. A signaling device comprising a motor, 80 a rotary compressor driven thereby, a horn body having a passageway in communication with the pressure side of the compressor and terminating at its upper end in a transverse tubular boss, a projector mounted in 85 said boss and in communication with said passageway, a cup-shape body threaded into the boss and in communication with the projector, a tube mounted in the boss and extending rearwardly into the cup-shape body, a cap threaded on to the cup-shape body, a diaphragm positioned between the cup-shape body and the cap and extending across the rear end of said tube.

6. A signaling device comprising a motor 90 having a casing including an end wall, said end wall formed with a cylindrical recess constituting a compressor chamber, a rotor 95 mounted in said chamber, a storage chamber partially surrounding the compressor chamber, and in communication with the pressure side of the compressor, a case enclosing the motor and an opening leading through the base of the compressor chamber to the interior of said case, said case formed with an opening permitting the entry of air to the chamber within it, and a fluid actuated signaling device in communication with said storage 100 chamber.

7. A signaling device comprising an electric motor, a rotary compressor including a rotor mounted upon the armature shaft of said electric motor, a horn body mounted 110 upon the compressor case and formed at its upper end with a tubular boss, a projector mounted in said tubular boss and having its axis disposed at right angles to the axis of the armature shaft, a tubular member mount- 115

- ed in the horn body, a diaphragm case having a tubular extension adjustably mounted in said boss and spaced radially from the said tube mounted in said boss, and a diaphragm 5 mounted in said diaphragm chamber and adjustable toward and from the end of said tube by rotary movement of said diaphragm case, and means for locking the diaphragm case in predetermined position.
- 10 8. A signaling device comprising an electric motor, a rotary compressor including a rotor mounted upon the armature shaft of said electric motor, a horn body mounted upon the compressor case and formed at its 15 upper end with a tubular boss, a projector mounted in said tubular boss and having its axis disposed at right angles to the axis of the armature shaft, a tubular member mounted in the horn body, a diaphragm case having a tubular extension adjustably mounted in said boss and spaced radially from the said tube mounted in said boss, a diaphragm 20 mounted in said diaphragm chamber and adjustable toward and from the end of said tube by rotary movement of said diaphragm case, means for locking the diaphragm case in predetermined position, an air storage 25 chamber around the compressor chamber and in communication therewith, and means of communication between the storage chamber and the diaphragm chamber through said tubular boss and the annular space between the tube mounted in the tubular boss and the tubular extension on the diaphragm 30 case.
9. A horn comprising a rotary motor provided with a front wall having a bearing for an armature shaft, said front wall including a rotor chamber eccentric with respect to said bearing, an armature shaft journaled in said bearing, a rotor in said chamber and connected to the armature shaft, a storage chamber partially surrounding the rotor chamber and in communication therewith.
- 40 45 10. A horn comprising a fluid compressor including a rotor chamber and a rotor arranged therein, a storage chamber partially encircling the rotor chamber and in communication solely with the high pressure side of the compressor, and an air resonant device in communication with the storage chamber.
- 50 55 60 11. A horn comprising a rotary motor provided with a front wall having a bearing for an armature shaft, said front wall including a rotor chamber eccentric with respect to said bearing, an armature shaft journaled in said bearing, a rotor in said chamber and connected to the armature shaft, and a storage chamber in communication with the rotor chamber.
- 65 12. A signaling device comprising an electric motor, a rotary compressor including a rotor mounted upon the armature shaft of said electric motor, a horn body mounted
- upon the compressor case, a projector mounted in said horn body, a tubular member mounted in the horn body, a diaphragm case having a tubular extension adjustably mounted in said horn body and spaced from the 70 said tube mounted in said horn body, a diaphragm mounted in said diaphragm chamber and adjustable toward and from the end of said tube, and means for locking the diaphragm case in predetermined position. 75
13. A signaling device comprising a front wall, a bearing for an armature shaft in the front wall, said front wall including a rotor chamber eccentric with respect to said bearing, an armature shaft journaled in said bearing, a rotor in said chamber and connected to the armature shaft, an electric motor including said armature shaft, an auxiliary chamber in communication with the rotor chamber, a horn body mounted on the casing, a projector mounted in said horn body, a tubular member mounted in the horn body, a diaphragm case having a tubular extension adjustably mounted in said horn body and spaced from the said tube mounted in said horn body, a diaphragm mounted in said diaphragm chamber and adjustable toward and from the end of said tube, and means for locking the diaphragm case in predetermined position. 80
- 85 90 95 100 105 110 115 120 125 130
14. A signaling device comprising a front wall, a bearing for an armature shaft in the front wall, said front wall including a rotor chamber eccentric with respect to said bearing, an armature shaft journaled in said bearing, a rotor in said chamber and connected to the armature shaft, an electric motor including said armature shaft, an auxiliary chamber in communication with the rotor chamber, a horn body mounted on the casing, a projector mounted in said horn body, a tubular member mounted in the horn body, a diaphragm case having a tubular extension adjustably mounted in said horn body and spaced from the said tube mounted in said horn body, a diaphragm mounted in said diaphragm chamber and adjustable toward and from the end of said tube, and means for locking the diaphragm case in predetermined position. 95
- 100 105 110 115 120 125 130
15. A pneumatic signaling device comprising a casting having a pair of projecting flanges and a cylindrical recess formed in the center to produce a rotor chamber, a U-shaped case having its ends secured respectively to said flanges, an armature shaft journaled in the U-shaped frame and said casting, a rotor in the rotor chamber connected to said armature shaft, a distributing chamber in said casting at one side of the rotor chamber, a horn body including a tubular portion, a projector mounted in said tubular portion, a tube positioned in and extending rearwardly from 130

said tubular portion, a diaphragm casing having a tubular extension threaded into said tubular portion and surrounding and spaced from a portion of said tube, a diaphragm in 5 said chamber extending across the mouth of the tube, and means for locking the diaphragm case with respect to the tubular portion.

16. A pneumatic signaling device comprising a rotary electric motor, a rotor chamber, a rotor therein connected to the armature shaft of said motor, a distributing chamber at one side of the rotor chamber, a horn body including a tubular portion, a projector 15 mounted in said tubular portion, a tube posi-

tioned in and extending rearwardly from said tubular portion, a diaphragm casing having a tubular extension threaded into said tubular portion and surrounding and spaced from a portion of said tube, a diaphragm in 20 said chamber extending across the mouth of the tube, and means for locking the diaphragm case with respect to the tubular portion.

In witness whereof we have hereunto set 25 our hands this 9th day of May, 1927.
